UNITED STATES PATENT OFFICE.

STANLEY K. REDDING, OF BLUFFTON, AND ORVA V. LANTIS, OF MARKLE, INDIANA.

BUCKLE.

Application filed September 7, 1922. Serial No. 586,628.

To all whom it may concern:

Be it known that STANLEY K. REDDING and ORVA V. LANTIS, citizens of the United States of America, residing, respectively, at 5 Bluffton and Markle, in the counties of Wells and Huntington and State of Indiana, have invented new and useful Improvements in Buckles, of which the following is a specification.

10 The object of the invention is to provide a fastening device of the buckle type suitable for rain coats and other like heavy outer garments and for over-all, blouses, suit cases and the like, which may be used 15 where an overlapping of the adjacent edges of the garment or closure is desired, and of such a construction as to permit of engagement and disengagement by one hand even though encased in a heavy glove; and with 20 this object in view the invention consists in a construction and combination of parts of which a preferred embodiment is shown in the accompanying drawings, wherein:—

Figure 1 is a view of a buckle embodying 25 the invention applied in the operative position to a garment or cover, the parts being shown in the engaged relation.

Figure 2 is a longitudinal sectional view 30 of the buckle with the parts united.

Figures 3 and 4 are views respectively of the blanks from which the parts or members of the buckle are formed.

The buckle consists essentially of the male and female or tongue and sleeve members 35 10 and 11 of which the former is provided with an attaching ear 12 from which the tongue 13 is offset to form a shoulder 14, said tongue being provided with a terminal transverse slot or opening 15. The attaching ear is provided with an opening 40 suitable for the reception of a rivet 16 or its equivalent.

The sleeve member consists of a cross sectionally rectangular sleeve 17 having a 45 terminal attaching ear 18 and a reinforcing plate 19 disposed in practice parallel with the base of the sleeve and substantially co-extensive therewith and provided in common with the ear 18 with an opening 20 so that a common rivet 21 serves to secure the same in place, the base and reinforcing plate lie upon opposite sides of the plane of the interposed fabric or flap 22 to which the buckle is attached and which is adapted to 50 be arranged in overlapping relation with that edge of the garment or closure to which

the tongue member is attached as will be obvious by reference to Figures 1 and 3.

At the inner end of the sleeve and projecting from the front wall thereof is a lug 23 invading the path of an object such as the tongue in passing through the sleeve and designed to engage the opening 15 in the end of the tongue. Also carried by and housed within the sleeve is a spring finger 24 which serves to impel the tongue 13 toward the front wall of the sleeve to insure the engagement of the opening 15 in the end thereof with the lug 23 as the tongue is pressed into the sleeve and moved longitudinally thereof. To disengage the tongue from the lug it is only necessary to press the free end of the tongue toward the rear wall or base of the sleeve and thus deflect the spring finger sufficiently to allow the 75 members of the buckle to be drawn apart.

The sleeve member of the buckle is preferably constructed from a single blank of sheet metal or its equivalent which as shown in Figure 3 embodies the main strip *a* which is adapted to be doubled upon itself longitudinally to form the base of the sleeve and the reinforcing plate 19 to lie upon opposite sides of the fabric or article to which the buckle is attached, said main strip being 80 slotted at *b* to provide a spring finger 24, and projecting from the side edge of said main strip is a wing *c* terminating in a leaf *d* so that when the wing is doubled upon itself to form the edge and front walls of 85 the sleeve, the leaf *d* may be inserted beneath the base of the sleeve or between said base and the article to which the buckle is attached to lie in co-extensive relation therewith, said leaf being provided with a rivet 90 opening 20 similar to those formed in the ends of the strip *a* to be engaged by a common rivet 21 which thus serves to hold the parts of the sleeve member of the buckle in their proper relation and at the same time 100 attach said member to the garment or article in connection with which it is to be used.

Having described the invention, what is claimed as new and useful is:—

1. A buckle having complementary members 105 of which one is provided with a tongue having a terminal opening and the other is provided with a sleeve for the reception of said tongue and carries a lug for engagement with the opening in said tongue, said sleeve 110 member consisting of a folded blank having a main strip foldable longitudinally to lie

- in contact with opposite surfaces of an interposed object and a lateral wing for transverse folding with relation to said strip to form the sleeve.
5. 2. A buckle having complemental members of which one is provided with a tongue having a terminal opening and the other is provided with a sleeve for the reception of said tongue and carries a lug for engagement with the opening in said tongue, said sleeve member consisting of a folded blank having a main strip foldable longitudinally to lie in contact with opposite surfaces of an interposed object and a lateral wing for 10 transverse folding with relation to said strip to form the sleeve, said wing being provided with a terminal leaf for arrangement between and in co-extensive relation with the terminally folded portion of the main strip.
3. A buckle having complemental members of which one is provided with a tongue having a terminal opening and the other is provided with a sleeve for the reception of said tongue and carries a lug for engagement with the opening in said tongue, said 25 sleeve member consisting of a folded blank having a main strip foldable longitudinally to lie in contact with opposite surfaces of an interposed object and a lateral wing for transverse folding with relation to said strip to form the sleeve, said main strip being slotted to provide a spring finger for arrangement within the folded sleeve.

In testimony whereof they affix their signatures.

STANLEY K. REDDING.
ORVA V. LANTIS.
